UNITED STATES PATENT OFFICE.

JESSE B. BRAUNSTEIN, OF ALLENTOWN, PENNSYLVANIA.

NITRO-STARCH EXPLOSIVE.

No. 868,837.

Specification of Letters Patent.

Patented Oct. 22, 1907.

Application filed July 18, 1907. Serial No. 384,305.

To all whom it may concern:

Be it known that I, JESSE B. BRAUNSTEIN, a citizen of the United States, residing in Allentown, Pennsylvania, have invented certain Improvements in the 5 Manufacture of Nitro-Starch Explosives, of which the following is a specification.

My invention relates to the production of graded nitro-starch blasting powders, and the object of the invention is to produce a cheap, stable and effective powder 10 of the grade desired.

As is well known nitro-starch, when produced by any practical commercial method, lacks stability and cannot be utilized as an explosive base, unless previously subjected to some stabilizing treatment, or unless a 15 stabilizing ingredient is included in the explosive mixture. It is also necessary in producing nitro-starch powders for commercial uses to add to the nitro-starch, a dope or moderating agent whereby the desired density and ratio of explosive force to a given weight of 20 powder are secured; the proportion of explosive base to added material determining the grade of the powder. I have discovered and disclosed in a copending application Serial No. 376,003 filed May 27, 1907, the fact that finely divided metal, such for example as iron 25 filings, may be used both as the moderating agent or dope and also the stabilizing ingredient, in connection with nitro-starch explosives. I have also discovered that the stability of a powder made up of nitro-starch and finely divided metal may be markedly increased by 30 the presence in the mixture of a comparatively small amount of a common nitrate, such for example as ammonium nitrate (NH_4NO_3). These three ingredients, nitro-starch, a nitrate and finely divided metal, are used in proportions varying according to the grade of 35 powder desired. The powder may vary from a 30% grade to 70% grade, that is to say, from one in which 30% of the entire mixture will be the explosive base, nitro-starch, to one in which the nitro-starch will be 70%, the balance in either case being made up of the 40 added materials. Of the added material from five to twenty per cent. will be nitrate, and the balance metal

filings. The amount of nitrate between the limits referred to may vary without substantially varying the strength or quickness of the powder, although the temperature of explosion will perhaps be slightly reduced 45 if as high as twenty per cent. of nitrate be used in the dope. The various ingredients are caused to be intimately intermixed in any convenient manner and if desired a small percentage of a suitable oil, for example, cotton-seed oil, say 1½% by weight of the entire mixture, may be added to give consistency.

Although I prefer to use finely divided iron as the metallic ingredient, other metals may be used, such, for example, as lead, zinc, or the common commercial 50 alloys.

I claim:—

1. An explosive consisting of an intimate mixture of substantially from 30 to 70 per cent. of nitro-starch, and substantially 70 to 30 per cent. of an added material comprising finely divided iron and a solid inorganic nitrate, 60 said nitrate constituting by weight substantially from 5 to 20 per cent. of the added material.

2. An explosive consisting of an intimate mixture of substantially from 30 to 70 per cent. of nitro-starch, and substantially 70 to 30 per cent. of an added material comprising iron filings and a solid inorganic nitrate, said nitrate constituting by weight substantially 5 to 20 per cent. of the added material.

3. An explosive consisting of an intimate mixture of substantially from 30 to 70 per cent. of nitro-starch, and substantially 70 to 30 per cent. of an added material comprising finely divided iron, and ammonium nitrate, said ammonium nitrate constituting by weight substantially 5 to 20 per cent. of the added material.

4. An explosive consisting of an intimate mixture of substantially from 30 to 70 per cent. of nitro-starch, and substantially 70 to 30 per cent. of an added material comprising iron filings, and ammonium nitrate, said ammonium nitrate constituting by weight substantially 5 to 20 per cent. of the added material.

In testimony whereof, I have signed my name to this specification, in the presence of two subscribing witnesses.

JESSE B. BRAUNSTEIN.
